THOMAS S. FELLOWS, OF WALNUT LAKE, MINNESOTA.

Letters Patent No. 80,538, dated August 4, 1868.

IMPROVED WEATHER-STRIP.

The Schedule referred to in these Letters Patent and making part of the same.

TO ALL WHOM IT MAY CONCERN:

Be it known that I, THOMAS S. FELLOWS, of Walnut Lake, in the county of Faribault, and State of Minnesota, have made certain Improvements in Weather-Strips; and do hereby declare that the following is a full, clear, and exact description of the same, reference being had to the accompanying drawings, and to the letters of reference marked thereon, and making a part of this specification, in which—

Figure 1 is a sectional view of a door with my weather-strip attached.

Figure 2 is a plan view of a door with my weather-strip attached.

Figure 3 is a sectional view in detail.

Figure 4 is a face view of the metal plates that form the strip.

I am aware that many devices have been employed to attain the desideratum at which I aim, and that metal strips or plates also have been used for the purpose, but I am not aware that metal strips have ever been used where the spring-action, which is actually necessary, has depended on and been supplied by the natural elasticity of the metal.

The nature of my invention, therefore, consists in attaching to a metallic plate an angular or wedge-shaped piece of wood, which, when the door is closed, entirely shuts off the ingress of draught, or the egress of heat between the door and its casement or frame. This plate is cast or struck up with an acute-angular groove or recess, so arranged as to receive the projecting lip or flange of the upper metal plate. This is all arranged on a suitably-grooved wooden plate attached to the face of the door, and should it be required to increase its power, the same can readily be done by inserting one or more wire fingers, having their bearings in the lower casement of the door, their free ends passing through a suitable aperture or opening in the lower plate, and its bearing at the angular turn of the upper plate.

To enable others skilled in the art to make and use my invention, I will now proceed to describe its construction and operation.

A is an ordinary door; B, the casement of frame; C, the metal plate, which may be either plain or grooved, with a struck-up lip, c' . D is a metal plate attached to the wooden weather-strip E. This plate is also struck up with an acute convex angular groove or recess, d' , in which works the lip c' . F is a metallic wire, which is inserted in the door, its free end resting against the angle of the lip c' . G is a lip which rests directly on the face of the grooved plate, by means of which the wire F can readily be operated.

Having thus fully described my invention, and the operation of the same, what I claim as new therein, and desire to secure by Letters Patent of the United States, is—

A weather-strip, composed of the plates C D, when the former is provided with a lip, c' , and the latter with an acute-angular groove or recess, d' , and the same are so combined and arranged that they are operated by the natural elasticity of the metal, substantially as described and for the purpose specified.

In testimony whereof, I have signed my name to this specification in the presence of two subscribing witnesses.

THOMAS S. FELLOWS.
